Primary Examiner—Wallace R. Burke*Assistant Examiner*—Marcus Jackson*Attorney, Agent, or Firm*—Woodard, Emhardt, Naughton, Moriarty & McNett[57] **CLAIM**

The ornamental design for a reflective road stud, as shown and described.

DESCRIPTION

FIG. 1 is a front elevational view of a reflective road stud showing my new design;

FIG. 2 is a side elevational view thereof, with the opposite side being a mirror image;

FIG. 3 is a sectional view taken along line 3—3 of FIG. 1;

FIG. 4 is a top plan view thereof;

FIG. 5 is a bottom plan view thereof;

FIG. 6 is a rear elevational view thereof; and,

FIG. 7 is a perspective view thereof.

FIG. 1.

FIG. 2.

FIG. 3.

FIG. 4.

FIG. 5.

FIG. 6.

FIG. 7.
